UNITED STATES PATENT OFFICE.

WILLIAM H. H. SISUM, OF BROOKLYN, NEW YORK.

MACHINE FOR UNLOADING AND UNBUNCHING MATCH-STICKS.

SPECIFICATION forming part of Letters Patent No. 355,416, dated January 4, 1887.

Application filed July 23, 1883. Serial No. 101,620. (No model.)

To all whom it may concern:

Be it known that I, WILLIAM H. H. SISUM, of Brooklyn, in Kings county, and State of New York, have invented a certain new and 5 useful Improvement in Machines for Unloading or Unbunching Match-Sticks, of which the following is a specification.

The object of this improvement is to produce a simple and compact machine for unloading or unbunching match-sticks, which have been bunched for the purpose of dipping them in the igniting material.

In the accompanying drawings, Figure 1 is a front view of a machine embodying my improvement. Fig. 2 is a back view of the same. Fig. 3 is an end view thereof, and Figs. 4 and 15 5 are detail views.

Similar letters of reference designate corresponding parts in all the figures.

20 A designates a shaft or arbor on which the bunch of match-sticks to be unloaded is placed. The bunch of match-sticks consists of two tapes or bands, B B', wound together with the match-sticks between them on a roller, A'.

25 The shaft or arbor A is provided with a spline or feather, and the inside of the roller A' with a recess fitting the spline. The roller is slipped on and off the shaft endwise.

The shaft A is supported in a frame, A³, 30 consisting of arms pivoted to the frame C and a cross-bar or stretcher connecting them.

The shaft A is clamped to one of the arms of the frame A³, so that it will not rotate too freely, but will produce a tension on the tapes 35 as they unwind.

The tape B passes around a roller, D, and fits within a peripheral groove therein. Before leaving the roller it passes between it and a small regulator-roller, E, whose shaft is supported near one end in a bearing which is pivotally connected to the frame, so that it may rock longitudinally. A spring, F, acting on this bearing causes this roller E to press against the tape B as it passes around the roller D, 40 thereby regulating the feed of the tapes. Leaving these rollers, the tape B passes to a roller, G, on which it is wound up. The roller G has an internal recess fitting a spline or feather extending from the shaft G', on which 45 it is mounted.

The tape B' passes a short distance around the roller D, and then passes in the reverse di-

rection around a roller, I, which is loosely mounted on a stud, I', and thence to a roller, H, on which it is wound. This roller H has 55 an internal recess fitting a spline or feather extending from the shaft H', on which it is supported. The shafts of the rollers G and H rotate in reverse directions. The said rollers serve to take up the slack of the tapes B B'. 60 They turn with their shafts, and can be slipped endwise on and off their shafts.

J is the driving-shaft of the machine. It is provided with a pulley, J', which has motion transmitted to it by a belt from any suitable 65 source of motion. It is also provided with a pulley, J², which receives a belt, J³, whereby motion is transmitted to a pulley, J⁴, on a shaft, K. The belt J³ may be tightened or slackened to cause it to drive or release the 70 pulley J⁴ on the shaft K.

I have shown a belt-tightener consisting of a bell-crank lever fulcrumed by a pin, a, to the frame C, carrying at one end a roller, J⁵, adapted to act on the belt J³, and pivoted at 75 the other end to a rod, J⁶. The rod J⁶ is connected at the lower end to one end of a lever, J', which is fulcrumed at about the middle of its length, and at the other end is provided with a foot-piece, which may be acted upon 80 by the attendant of the machine. By depressing the foot-piece the roller J⁵ is made to act upon and tighten the belt, and by releasing the foot-piece gravity acts to remove the said roller from the belt.

85 The shaft K is provided on one end with a large gear-wheel, K', and a smaller gear-wheel, K², which are rigidly affixed to it. The gear-wheel K' engages with a gear-wheel, H², mounted on the shaft H', on which the roller H is supported, and thereby imparts motion to this roller. The gear-wheel K' also engages with a gear-wheel, L, which is mounted upon a shaft, I', that is journaled in the frame C. The gear-wheel L engages with a gear-wheel, 90 G², which is mounted on the shaft G', whereby the roller G is supported. The gear-wheel G² and the gear-wheel H² are clamped to their respective shafts, so that either the gear-wheel or shaft may slip relatively to the other. The gear-wheel K² engages with a gear-wheel, E', 95 on the shaft of the roller E. The roller E, being thus positively rotated in contact with the tape B, draws that tape along, and by the ten-

sion of the tape which it produces aids in unwinding the tapes B B' from the roller A'. This is important, for, owing to the manner in which the wheels G² H² are secured to their shafts G' H', merely by friction-clamps, they might prove insufficient to unwind the tapes from the roller A' if unaided by other means.

Fig. 4 clearly illustrates the manner in which the gear-wheels G² H² are clamped to the shafts G' H'. On each shaft is a shoulder, and next to this shoulder fits a disk-shaped clamp, M. Next the clamp M fits the gear-wheel, and next the gear-wheel is another disk-shaped clamp, M'. Outside the clamp M' is a nut, M², and it fits a screw-thread on the shaft. A jam-nut, M³, fits on the screw-thread of the shaft outside the nut M². The clamps have in the sides next the gear-wheels cavities, in which fit packings of leather or other suitable material.

The shaft A is clamped to the arm of the frame C in just the same way that the shafts G' H' are clamped to the gear-wheels G² H².

The match-sticks are longer than the roller D is wide; hence they extend not only over but beyond the edge portions of the said roller which form the sides of its peripheral groove. This groove is just about large enough to accommodate the tape B.

At the sides of the roller D are strippers N, which for a considerable distance are concentric and coincident with the side portions of the said roller. Beyond the point where the tapes are caused to diverge around the rollers D I, these strippers have portions s, which extend in lines tangential to the side portions of the roller D. These tangential portions extend at a downward inclination toward their outer ends, and strip or lift the match-sticks from the roller D and form a chute over which the match-sticks may be discharged. Guards O, consisting of small rods or wires, extend over these tangential portions of the strippers, and prevent the match-sticks from escaping therefrom except over the ends. The strippers are fastened by screws to a bar, N', which is secured to the main frame of the machine. The guards are secured in holes or sockets in the stud I, which supports the roller I.

It is advantageous to secure the wheels G² H² to their shafts by friction-clamps, in order that the tapes B B' shall be wound snugly on their rollers.

A machine having friction-clamps applied to the shafts of the bunch or delivery roller

and the take-up rollers may be made much more compact than one in which belts are used sufficiently slack to slip.

When the tapes are all wound on the take-up rollers G H, the latter are slipped off and placed in a machine wherein match-sticks are bunched for dipping them in the igniting material.

What I claim as my invention, and desire to secure by Letters Patent, is—

1. In a machine for unloading or unbunching match-sticks, a delivery or bunch roller for holding tapes, a shaft for said roller connected with its bearings by a friction-clamp, take-up rollers for receiving the tapes, gear-wheels connected by friction-clamps with the shafts of said take-up rollers, rollers around and over which said tapes pass and diverge, and a positively-driven regulator-roller acting in conjunction with one of the rollers around which tapes pass at the point of divergence, all being so combined and organized that the regulator-roller will cause the tapes to be moved at a uniform speed irrespective of the diameters of the portions of the tapes wound upon the delivery or bunch roller and the take-up rollers, that the delivery-roller may slip to accommodate itself to the speed of the regulator-roller, and that the take-up rollers will only rotate with a force sufficient to take up the slack of the tapes, and not with a force sufficient to interfere with the proper action of the regulator-roller, substantially as specified.

2. In a machine for unloading or unbunching match-sticks, the combination of a delivery or bunch roller for holding tapes, a shaft for said roller connected with its bearings by a friction-clamp, take-up rollers for receiving and taking up tapes, gear-wheels connected by friction-clamps with the shafts of said take-up rollers, rollers around or over which said tapes pass and diverge, strippers N, which are for a distance concentric with the side portion of the roller and have tangential portions extending at a downward inclination toward their outer ends, guards O, extending over the downwardly-extending tangential portions of said strippers, and a positively-driven roller acting in conjunction with one of the rollers around which tapes pass at the point of divergence, and serving to regulate the feed of said tapes, substantially as specified.

WM. H. H. SISUM.
